UNITED STATES PATENT OFFICE.

JAMES CRABB, SR., OF JOLIET, ILLINOIS.

VIBRATING SCREEN.

Application filed November 26, 1926. Serial No. 150,823.

My invention relates to a vibrating screen and has for its primary object the provision of a screening device for use in screening coke for the removal of the fine particles 5 of coke, breeze, dust and the like from the coke without breaking the particles of coke, and in which the abrading action of the pieces of coke is reduced to a minimum.

Another and further object of my invention is the provision of a screening apparatus which effectually removes coke dust and fine particles and broken pieces of coke from the larger material without subjecting the coke to hard shocks or to an abrading movement over the screen so that the dust and fine particles of coke are removed from the larger pieces and not carried over the screen attached to or supported by the larger pieces of coke, as is common with the present type 20 of screens, or the coke broken in finer particles, the screens being so mounted that they vibrate or rock about the center of the screens.

Another and further object of my invention is the provision of a coke screen apparatus in which the pieces of coke as they pass over the screen are vibrated in different degrees so as to cause the coke to pass over the screen by vibration and not slide 30 upon the screens and yet thoroughly remove the small particles of coke from the major portion as it passes over the screen.

Another and further object of my invention is the provision of a screen having a 35 rocking vibratory action imparted thereto by means of which the material which is being screened is caused to travel over the screening surface by being thrown across the screening surface in a series of steps rather 40 than being slid across the surface, thus resulting in a minimum of abrading action of the coke as it passes over the screens and also in which a plurality of screens are arranged in such relation to each other that decreasing movement is imparted to the coke 45 as it passes over the screens, the first movement being the most violent in order that the fine particles be separated from the mass and also to remove the dust and dirt carried 50 by the pieces themselves.

These and other objects of my invention will be more fully and better understood by reference to the accompanying sheets of drawings and in which:

Figure 1 is a side elevational view of my

improved invention, portions of which have been removed or broken away to more clearly illustrate the construction; and

Figure 2 is an end elevational view of the apparatus shown in Figure 1 in which certain portions of the supporting framework and the spring means have been omitted for purposes of clearness.

Referring now specifically to the drawings, a pair of transversely extending beams 65 10 and 11 are shown adapted to support a pair of sills 12 and 13 extending longitudinally of the screening device, these sills having a pair of angles 14 and 15 extending longitudinally thereof, these members forming the base framework for the screening apparatus hereinafter described. An upper screen support is provided comprising a pair of standards 16, which are suitably secured to the angles 14 and 15 and braced 70 by brackets 17 with a second pair of upright members 18 being provided, these members being angularly disposed with reference to the members 16 and slightly shorter than these members. It will be understood that Figure 1 only shows the side members on one side of the complete construction. Thus there is a standard on the opposite side corresponding to the member 16 which is not shown. The same will apply to other members which are substantially duplicates of the members referred 80 to and therefore are not illustrated. At the upper ends of the members 16 and 18 and connected thereto, is a pair of angularly extending lower frame members 19 and a pair of upper frame members 20, these members being diagonally disposed so that the screen when mounted thereon is tilted at an angle of approximately 25° to a horizontal plane. 85

Mounted upon the members 19 on each side of the framework, is a plurality of upper and lower bearing brackets 21, through which a pair of shafts 22 and 23 extend, having gear wheels 24 and 25 thereon adapted to mesh with each other, the shaft 22 having a driving pulley (not shown) secured thereto by means of which the whole apparatus is driven by a belt attached thereto and leading to any suitable source of power. Mounted upon the upper frame members 20 is a pair of bearing blocks 25* which are secured to the frame member in any suitable manner and which have V-shaped recesses 26 in the upper sides thereof 105 110

adapted to receive a cross bar 27 with pins 28 extending through the brackets 25^a and through the rocker brackets 27 so as to hold the screens in proper position. A frame 29, 5 rectangular in shape, is provided having a screen 30 mounted thereon in any suitable manner and having a plurality of extensions 31, 31 extending outward therefrom at each of its corners, and thence downward 10 into a V-shaped form between the outer ends of which are rollers 32, 32 mounted upon pins 32^a. The frame 29 has a plurality of spaced trunnions 33 located on the under side thereof at each of its sides. The rocker bar 27 is adapted to rest between each 15 pair of trunnions at each of the ends of the frame 29 with a pair of pins 34 extending through the trunnions 33 by means of which the frame 29 is secured to the brackets 25. 20 A plurality of two-way springs 35 are placed under the frame 29 at each of the corners thereof and are mounted upon the upper side frame members 20 in any suitable manner, these springs permitting vibration or 25 rocking of the screen and frame 29 in the brackets 25^a when the device is in operation, as hereinafter described. The springs 35 on one side only of the apparatus have been illustrated, but it will be understood 30 that corresponding springs are provided on the opposite side but are not shown.

Mounted upon the shaft 22 adjacent each of its ends is a pair of drums 36, 36 having a plurality of arms 38, 38 mounted thereon 35 and extending outwardly beyond the outer periphery thereof at right angles to each other, said arms 38 having their outer ends turned backwards in a direction opposite to the travel of the drums and adapted to engage against the rollers 32 in the extensions 31 at the upper corners of the frame 29, so that as each one of the arms 38 strike the roller, the screen is given a rocking or an oscillatory movement. A pair of drums 37 40 are mounted upon the shaft 23 adjacent the ends thereof, with a plurality of arms 39, 39 upon each of these drums which extend at right angles to each other, the outer ends of which are angularly disposed, and in a 45 direction opposite to the arms 38, 38 for the reason that the drums 37 turn in a direction opposite to the drums 36, the ends of the arms 39 being adapted to engage the rollers 32 in the extensions 31 at the lower side of 50 the frame 29, and giving the lower side of the frame 29 an upward movement, the rotation of the drums 36 and 37 being such that the screen is vibrated by engagement of the arms 38 and 39 with the rollers 32, so that 55 the screen 30 is given a vibratory rocking action upon the bar 27 mounted upon the bearing blocks 25^a, the extent of its movement at its upper and lower sides depending upon the strength of the springs 35, 35 60 at each of its corners.

A delivery roller 40 is provided over which the coke is passed onto the upper side of the screen 30 and as the device is operated, the screen having been given a rocking action, shakes out the particles of dust 70 through the screen, where it falls into a chute placed below the screening device in any suitable manner.

A second screening unit is provided which is supported at its lower end by a pair of 75 vertical frame members 41, which have secured thereto a plurality of lower frame members 42 and upper frame members 43, the upper frame members carrying a pair of bearing blocks 44, within which a frame 80 45, having a screen 46 secured thereto, is positioned, by means of a transversely extending rocker bar 47 seated in V-shaped recesses 48 in the upper side of the bearing blocks 44. A pair of trunnions 49 and 50 85 are formed on the under side of the screen member 45 on each side thereof, between which the rocker bar 47 is placed. A pair of gear wheels 51 and 52 are mounted upon shafts 53 and 54 respectively, with a plurality of drums 55 and 56 mounted upon each end of the said shafts 53 and 54 respectively, the gear wheels 51 and 52 being in mesh with each other and the gear wheel 51 meshing with the gear wheel 25 so that 90 as the upper section of the screen is operated, the screen 46 will also be operated at the same time. The screen frame 45 has a plurality of two-way springs 57 mounted under each corner thereof with a plurality of extensions 58, 58 extending downward therefrom at each of the corners thereof, with rollers 59, 59 positioned therein adapted to be engaged by a plurality of arms 60, 60 95 carried by the drums 55 and other arms 61, 61 carried by the drums 56, each of the drums 55 and 56 having three screen rocking arms placed thereon in equal distant relation with each other at an angle of approximately 120° thereto so that the screen 100 46 is operated at a slightly lower rate of speed than the screen 30. Suitable bearing blocks 62, 62 are provided which are secured to the lower frame members 42 in any suitable manner, providing mountings for 105 the shafts 53 and 54 at each of their ends.

At the lower end of the device a pair of longitudinally extending lower frame members 63 are provided which are secured at their upper ends to the angularly disposed members 41 and are secured to the outer ends of the angles 14 by a pair of brackets 64, a pair of upper frame members 65 being provided, the upper ends of which are secured to the diagonally extending member 41, and also to a pair of posts 66, with a plurality of bearing blocks 67, 67 being provided which are mounted to the diagonally extending sills 63 and within which shafts 68 and 69 are placed, each of these shafts 110 115 120 125 130

having drums 70 and 71 adjacent their ends, each of the drums 70 having a pair of arms 72, 72 secured thereto which extend outward from each other on diametrically opposite sides of the drums 70. Arms 73, 73 are also extending outward from each other on diametrically opposite sides of the drum 71 and so timed that they operate in alternate relation with the arms 72 carried by the drum 70. A pair of gear wheels 74 and 75 are provided which are in mesh with each other, the gear wheel 74 also being in mesh with the gear 52 so that as the upper screens 30 and 46 are oscillated, a lower screen 76, mounted upon a frame 77, is also oscillated by the action of the arms 72 and 73. The frame 77 at each of the corners thereof, has a plurality of extensions 78, 78 thereon having rollers 79 in the outer ends thereof with two-way springs 80 positioned upon the frame members 65 and mounted under the frame member 77 at each of the corners thereof, so that as the arms 72 and 73 engage against the rollers 79, the screen 76 is given a rocking action, this rocking action being slower and therefore less violent than the movement given to each of the other screens heretofore described. A pair of brackets 81 is provided having V-openings 82 in the upper sides thereof within which a transversely extending member 83 is positioned which is placed between a pair of trunnions 84 and 85 formed on the under side of the frame member 77 with a pin 86 extending through the brackets 81 and through the transversely extending member 83 and with other pins 87 extending through the trunnions 84 and 85 and through the transversely extending member 83 so that the frame 77 is held in position in the brackets 81.

In operation of the device the coke, or other material to be screened, is delivered over the drum 40 and deposited on the upper side of the screen 30 and as the device is operated, the arms 38, 38 striking against the rollers 32 give this screen a rapid vibratory rocking action, tossing the pieces of coke on the screen and shaking them rapidly so that the dust and fine particles of coke are removed from the mass and pass through the screen, this screen preferably operating at approximately 96 times per minute. The material passes downward over the screen 30 onto the screen 46 where it is given a further shaking and other particles of dirt and dust removed therefrom, this screen being operated at approximately 72 times per minute and the coke therefore not receiving such a violent shaking as it does on the first screen and which is adapted to thoroughly remove and to shake loose the particles of dust adhering to the pieces of coke, in addition to removing the dust and loose particles from the mass. The material passes downward over the second screen onto the third

unit which oscillates at approximately 48 times per minute, this screen being operated more slowly in order that the dust and dirt may be merely shaken out of the screen without subjecting the particles or pieces of coke to such violent agitation as to break the pieces, the dust and small particles of coke which are removed from the particles dropping through the screen and into a chute provided for receiving these particles, underneath the screen. The screened coke after passing over the screens is deposited into a chute or onto a receiving belt as may be desired.

It will be thus understood that I provide a screen having a rocking resilient action by reason of the springs mounted under each corner, one unit of which operates rapidly in order to not only shake the particles of dust and dirt out of the larger particles, but also to remove the dust and dirt adhering to the larger particles of coke, and as the coke passes over this screen and is deposited onto a second screen the action is less violent, being adapted merely to shake the particles of dust and dirt out of the coke and that the last screen is still less violent and operated more slowly so that the dirt is removed from the coke with as little breakage as possible and also with as little abrasion action as possible with the pieces of coke one against the other in order to reduce the formation of dust to a minimum during the screening operation. It will be noted that the screens are placed in angular relation so that there is a tendency of the coke to slide across the screen by gravity, but the rocking action of the screen causes the coke to travel thereover in a series of jumps or loops with one movement of the screen tending to cause the coke to travel over the screen toward the discharge side thereof and the second movement of the screen from the opposite end throwing the particles of coke upward so that the tendency is to retard its movement and also to turn the particles of coke over so that they will not pass over the screen with particles of dust and dirt adhering to the upper surface of the coke.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In combination a screen, a frame upon which said screen is mounted, a central mounting member for said screen, springs secured to said frame and also to said screen at each of its ends, depending arms from said screen, a plurality of drums and arms

mounted on said drums, said arms being so placed on said drums that a rocking movement is imparted to said screens.

2. In combination, a screen, a frame upon which said screen is mounted, a plurality of springs at each end of said screen, a plurality of arms depending from said screen, a pair of shafts, a plurality of arms secured to said shafts adapted to contact with the arms secured to said screen, a pair of gear wheels adapted to operate said arms in timed relation with each other, whereby the arms are alternately brought in contact with the screen at each of its ends.

15 3. A screening device comprising in combination, a main frame, a plurality of screen frames, blocks mounted on said main frame in central position with respect to said screen frames, rocking bars secured to the said screen frames and to said blocks, springs mounted between the screen frames and the main frame, trunnions on said screen frames, a plurality of rotating drums, connecting means for said drums, and arms mounted 20 on said drums in different spaced relation with each other and adapted to engage said trunnions whereby a decreasing movement is progressively given to the said screens.

4. In a screening device the combination 30 of a main frame, a plurality of screen frames, screens mounted on said screen frames, mounting members secured to said screen frames intermediate the ends of the screen frames, rocking bars connected to said screen frames and to said mounting means, springs positioned between the said main frame and said screen frames at each of the ends thereof, a plurality of trunnions on said screen frames, rotating drums under 35 each end of said screens, and arms on said drums adapted to contact with the said trunnions, the drums under each screen having a progressively lesser number of arms thereon towards the discharge end of said screen.

45 5. In a screening device, the combination of a main frame, a plurality of screen frames, screens mounted on said screen frames, mounting members secured to said screen frames intermediate the ends of the 50 screen frames, rocking bars connected to

said screen frames and to said mounting means, springs positioned between the said main frame and said screen frames at each of the ends thereof, a plurality of trunnions on said screen frames, rotating drums under 55 each end of said screens, and arms on said drums adapted to contact with the said trunnions, the arms on each cooperating pair of drums being similarly spaced but spaced in different relation with respect to each pair of drums whereby a progressively decreased frequency of speed is given to the said screens.

6. A screening device comprising in combination, a main frame, a plurality of screen frames, a pair of blocks having recesses on their upper sides mounted on said main frame intermediate the ends of said screen frames, rocking bars mounted in the recesses in said blocks and connected to the said screen frames, springs mounted on said main frame and under the screen frames at each of the ends thereof, trunnions at each end of the said screen frames, a plurality of drums mounted on said frame, arms on said drums, 60 and gears connecting the said drums, the arms on the drums operating each screen, decreasing progressively towards the discharge end of the screen.

7. A screening device comprising in combination, a main frame, a plurality of screen frames having a pair of spaced trunnions thereon, a pair of blocks having recesses on their upper sides mounted on said main frame intermediate the ends of said screen 85 frames, rocking bars mounted in the recesses in said blocks and connected to the said screen frames, springs mounted on said main frame and under the screen frames at each of the ends thereof, trunnions at each end 90 of the said screen frames, a plurality of drums mounted on said frame, arms on said drums, and gears connecting the said drums, the arms on the drums operating each screen, decreasing progressively towards the discharge end of the screen.

Signed at Joliet, Illinois, this 17th day of November, 1926.

JAMES CRABB, Sr.
